CLAIM

The ornamental design for an electric tricycle, as shown and described.

DESCRIPTION

FIG. 1 is a top, front and left side perspective view of an electric tricycle embodying my new design;

FIG. 2 is a bottom, rear and right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is an enlarged and partial perspective view of area 9 in FIG. 1;

FIG. 10 is an enlarged and partial perspective view of area 10 in FIG. 1;

FIG. 11 is an enlarged and partial perspective view of area 11 in FIG. 1;

FIG. 12 is an enlarged and partial perspective view of area 12 in FIG. 2; and,

FIG. 13 is an enlarged and partial perspective view of area 13 in FIG. 2.

The dot-dash broken lines do not illustrate actual structure and only show the area of enlargements. The depicted enlargements shown in full solid lines form part of the claimed design, while the dot-dash broken lines do not.
